J. J. BEHM

SHAPER GUIDE

Filed Dec. 1, 1922

Inventor

John J. Behm,

Schiel J. Biley

Attorney

UNITED STATES PATENT OFFICE.

JOHN J. BEHM, OF GRAND HAVEN, MICHIGAN.

SHAPER GUIDE.

Application filed December 1, 1922. Serial No. 604,297.

To all whom it may concern:

Be it known that I, JOHN J. BEHM, a citizen of the United States, residing at Grand Haven, in the county of Ottawa and State of Michigan, have invented certain new and useful Improvements in Shaper Guides, of which the following is a specification.

My invention relates to improvements in guides for shaping articles upon a power shaper, and particularly for shaping toilet seats, and its objects are: first, to provide a means whereby the operator may have a clear view of his work without danger of having his eyes filled with dust etc.; second, to provide a means whereby the seats may be readily and accurately clamped into the guide; third, to provide a means whereby the openings in the seats may be properly shaped with less expenditure of time and labor than is necessary with ordinary guides, and, fourth, to provide a means whereby the seats to be shaped may be readily and easily clamped upon, and removed from the guide.

I attain these objects by the mechanism and construction of parts shown in the accompanying drawing, in which Fig. 1 is an elevation of the guide complete. Fig. 2 is a sectional elevation of the same. Fig. 3 is a top plan, and Fig. 4 is a bottom plan of the same, Fig. 5 shows the position of the guide when inserting a seat therein, and Fig. 6 is an edge elevation of the same.

Similar numerals indicate similar parts throughout the several views.

In the construction of this guide I make a base 1—1' having an opening 15 through the part 1' and a like opening through the part 1, except that the opening through the part 1 has an offset 16 therein designed to carry the seat material a little further from the knives 27 at the front, and make the curvature of the surface of the material a trifle more abrupt than at the sides and back, as indicated at *b*, compared with the form at *a*, in Fig. 2, the edges of the opening 15 being designed as a guide for the roller 19 to travel upon for shaping the edges *a*—*b* of the seat. The roller 19 is designed to be made adjustable, or slidable upon the shaft 17, as indicated by the solid and the dotted lines in Fig. 2 so as to change the form of the shaping if desired.

For clamping the seat pattern into the guide I place sharp spurs, 13, into the back supporting rail 5' designed to enter the edge 55 of the seat 12, as indicated in Figs. 1 and 2, and at the other end of the guide I place a retaining lever 7, having an engaging spur 7' designed to be forced into the edge of the seat by means of the screw 10 working 60 through the support 9, and operated by the crank 10', the lever 7 being pivotally connected with the hinge 6, as at 3, in such a manner that when the point or spur 7' is forced into the edge of the material to be 65 shaped, it will have a tendency to draw the material against the lower surface of the base 1, 1' sufficiently to avert any danger of the slightest vertical movement or trembling of the material when being acted upon by 70 the shaper knives. I, also, place an actuating spring 11 in the base or bed 1, 1' in position to force the spur out of contact with the cover when the lever 7 is released from the pressure of the screw 10. When the seat 75 12 has been properly clamped upon the guide base 1 the seat is placed with its exposed surface upon the upper surface of the shaper bed 14, with the roller 19 bearing upon the surface of the inner edge of the 80 guide to enable the operator to hold the work firmly against the revolving knives 27 when being shaped.

At 5 I have shown an upwardly extending bearing designed to act as a support to 85 hold the guide in vertical position when inserting or removing a cover, and 4, 4 represent standards or handles by means of which the operator may hold and guide the implement as desired, and by means of which the 90 guide may be held firmly to the work when shaping the inner and upper surface of the seat.

25 represents an opening through the bed 14 of the shaper frame through which the 95 shavings from the shaper knives 27 are made to pass into the receiver 23, whence they are forced through the pipe 24 by means of an appropriate blower fan, not here shown as it has no direct connection with this invention. 100

For the purpose of providing a means whereby a perfect view may be had of the working parts of the machine without danger of dust, shavings, etc., being blown

into the face and eyes of the operator, I form a cylindrical chamber or dome 2 upon the upper surface of the part 1 of the guide and secure it by some available means for 5 the purpose, as, for instance, by means of a securing ring 3 securely connected with the bed 1 and with the walls of the dome 2. In the top of the dome 2 I place a transparent cover, as of glass, celluloid or kindred material, as indicated at 20, which may be held 10 securely in place by any of the usual means employed for such purposes, as, for instance, I sometimes place a lining plate 22 inside of the dome wall 2 upon the edge of which the 15 edge of the top 20 may be made to rest, and to hold the top in place an open cap or border 21 may be placed over the edges of the top 20 and downwardly over the upper end of the dome wall, as indicated in Fig. 2. By 20 this means, it will be readily understood that this transparent top, 20, may be left absolutely unobstructed, and with the blower carrying the shavings and dust out through 25 the pipe 24, and the dome thoroughly enclosed with the transparent top 20, it will be possible to plainly see the operation of the shaper knives without the least danger of dust, etc., filling the atmosphere above the 30 shaper bed and greatly inconveniencing the operator, as is usual when the work is left exposed, no matter how perfectly the blower

may be operating in carrying off the shavings and dust from the machine.

26 represents an ordinary collar upon the shaft 17 for holding this shaft in proper 35 vertical position in its retaining boxes.

Having thus fully described my invention, what I claim as new and desire to secure by Letters Patent, is:

1. In combination with a guide for shaping the openings in toilet seats, a form body having stationary spurs at one end for engaging the edge of the material to be shaped, an adjustable spur pivotally mounted above the edge of the base at the other end and extending downwardly into position so the points may be made to penetrate the edge of the material to be shaped, and a spring chambered in the base in position to force the spur out of engagement with the material when its pivotal body is released, and a screw and rack for forcing the spur into engagement with the material. 40

2. In combination with the elements covered in claim 1, a crib mounted upon the 55 base around the opening therethrough, and an unobstructed transparent cover over said crib.

Signed at Grand Haven, Michigan, October 18, 1922.

JOHN J. BEHM.
